CLAIM

The ornamental design for an air purifier, as shown and described.

DESCRIPTION

FIG. 1 is a perspective view of an air purifier showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 2;

FIG. 11 is an enlarged view of a portion indicated with numeric 11 in FIG. 2;

FIG. 12 is an enlarged view of a portion indicated with numeric 12 in FIG. 3; and,

FIG. 13 is an enlarged view of a portion indicated with numeric 12 in FIG. 8.

The broken lines in drawing show portions of the air purifier that form no part of the claimed design. The additional broken lines in the figures illustrate the boundaries of the enlarged view indicators and form no part of the claimed design.

1 Claim, 10 Drawing Sheets
